UNITED STATES PATENT OFFICE.

JOSEPH H. GLAUBER, OF CLEVELAND, OHIO.

DESIGN FOR AN ELBOW-COUPING.

SPECIFICATION forming part of Design No. 31,553, dated September 26, 1899.

Application filed August 26, 1899. Serial No. 728,633. Term of patent 14 years.

To all whom it may concern:

Be it known that I, JOSEPH H. GLAUBER, a citizen of the United States, residing at Cleveland, in the county of Cuyahoga and State of Ohio, have invented and produced a new and original Design in Elbow-Couplings, of which the following is a specification, reference being had to the accompanying drawing, forming a part thereof.

10 The invention has reference to elbow-couplings designed more especially for open-work plumbing, where neatness of appearance is a prime consideration.

15 The design is fully illustrated in the perspective view of the coupling seen in the accompanying drawings; and it consists, essentially, in an elbow A with an attractively-finished surface and having a terminal enlarge-

ment a at one end, which is relieved over both its inner and outer surfaces with a series of 20 elevations 2 and depressions 3, alternately within and without, and alike clearly exposed at the end and constituting the distinguishing mark of said enlargement and of this part of the design. A continuous uniform facing 25 b marks the edge-finishing of the enlarged end of the design.

What I claim is—

The design for an elbow-coupling, substantially as shown and described.

Witness my hand to the foregoing specification this 16th day of August, 1899.

JOSEPH H. GLAUBER.

Witnesses:

H. T. FISHER,
R. B. MOSER.
